APPARATUS FOR PUNCHING AND
WORKING METALArchibald M. Brown, Trenton, Mich., assignor to
The Firestone Tire & Rubber Company, Akron,
Ohio, a corporation of Ohio

Application September 13, 1939, Serial No. 294,662

2 Claims. (Cl. 113—42)

This invention relates to punching and working metal, more especially to punching or trimming metal having a hole therethrough to enlarge the size of the hole, and thereafter drawing the portion of the metal adjacent the hole to form a protuberance on the metal.

Heretofore standard practice in punching holes through sheet metal has been to provide a clearance between the punch and the die of approximately 10% of the thickness of the metal. When punching thin metals, for example of .02 inch thickness, this permits a clearance of only .001 inch on each side of the punch as it enters the die. Thus any slight vibration of the machine will cause the punch to hit the side of the die and spoil the hole produced in the sheet metal. Also, any roughness in the edges of the punched hole, especially in stainless steel, produces splits in the metal, if it subsequently is drawn or otherwise worked to form an outwardly extending boss, or other member on the sheet metal. Usually after a hole is punched in a piece of sheet metal, the hole is made clean and smooth by buffing or reaming same, and then the metal adjacent the hole is drawn to the desired shape.

One general object of this invention is to provide an improved, uncomplicated method of forming a smooth hole through metal and to provide sturdy, inexpensive machinery for practicing the method.

Another object of the invention is to simplify and reduce the cost of punching a hole in a sheet metal member and thereafter in the same operation, drawing the metal adjacent the hole outwardly therefrom to form an integral boss on the sheet metal member.

Other objects of the invention will be manifest from the following specification, which will be described with particular reference to the accompanying drawings, in which:

Figure 1 is a vertical cross sectional view of apparatus embodying the invention at the starting point of its operation;

Figure 2 is a similar view of the apparatus of Figure 1 with the punch in engagement with the die;

Figure 3 is a view of the apparatus of Figure 1 in its final position with the upper member in engagement with the die; and

Figure 4 is a section through the integral bung formed on a sheet metal member by practice of the invention.

Broadly speaking, the present invention comprises the steps of forming an aperture of less

5 than the desired size in a piece of sheet metal and partially drawing, or pressing out the metal thereadjacent, and thereafter trimming the aperture to the desired size by a punch having a centering member associated therewith. Initial movement of the punch engages the centering member with a bushing carried in a hollow die to center the punch with relation to the die, after which the centered punch, on continued movement thereof, engages with the die and trims the aperture in the sheet metal to the desired size. As the member carrying the punch and centering member continues to move toward the hollow die, it draws or presses out the metal adjacent the trimmed aperture by engaging with the outside 15 of the die.

The present invention will be described particularly with reference to the provision of an integral boss on a stainless steel sheet metal member such as is used in the construction of beverage containers, although it will be apparent that the invention may be used merely to form a smooth, polished hole through any desired metal member, or that other types of drawn metal protuberances on apertured metallic objects may be formed by practice of the invention.

Referring specifically to the apparatus shown in Figure 1, it includes a suitably mounted base plate 10 which has a central recess 11 and a plurality of smaller recesses 12 formed therein, the small recesses 12 being formed in a circle around the recess 11 or in parallel rows on both sides of the recess 11, as desired. A hollow die 13 is snugly received in the recess 11 and thereby 20 mounted upon the base plate 10. The hollow die 13 has a bore 14 which has a reduced diameter adjacent the upper end thereof, with a centering bushing 15 being received in the bore 14. This bushing 15, having a bore 16, has a small flange 25 formed thereon adjacent its base, which flange engages with a shoulder 18 formed in the centering bushing at the reduced diameter thereof. Normally the centering bushing 15 is held in engagement with the shoulder 18 by a spring 19 which also is within the centering die 15 and which bears upon the base plate 10. In order to mount a sheet metal member 21 upon the hollow die 13, a supporting plate 22 is carried by the base plate 10 by a plurality of springs 23 which engage with the recesses 12 of the base plate and with corresponding recesses 24 formed in the supporting plate. Before positioning the sheet metal member 21 on the supporting plate 22, it will be observed that a hole 25 has been formed therein and that the portion 26 of the

sheet metal member thereadjacent has been drawn or pressed out slightly from the plane of the remainder of the member.

The punching apparatus of the invention comprises a cylindrical punch 27 which is mounted in an upper member 28 that is movable relative to the base plate 10 and the apparatus carried thereon. The upper member 28 has a cylindrical recess 29 formed therein immediately adjacent the cylindrical punch 27, which is received within the periphery of the upper member. The punch 27 is centered relative to the hollow die 13 by a centering finger 31 which is carried by the punch and which extends downwardly from the center of the punch. The centering finger 31 has a tapered end portion 32 which is adapted to engage with the centering bushing 15 when the upper member is moved downwardly relative to the base plate and center the punch 27 relative to the hollow die 13. In engaging with the centering bushing, the centering finger extends through the hole 25 formed in the sheet metal member 21.

Thus upon downward movement of the upper member relative to the base plate, the centering finger first engages with the centering bushing and then the cylindrical punch shears off, or trims the metal adjacent the hole 25 due to the punch passing within the hollow die 13. In passing into the hollow die, obviously the centering punch 27 depresses the spring 19 and the centering bushing 15 (Figure 2).

Continued downward movement of the upper member acts to engage the cylindrical recess 29 with the outer portion of the hollow die 13. In doing this, the upper member 28 further draws out the pressed out portion 26 of the sheet metal member 21 until it is perpendicular to the remainder of the sheet metal member, as shown in Figure 3. The outer portion of the end of the hollow die 13 is rounded off as at 33 to facilitate the initial drawing or bending of the sheet metal member due to engagement with the upper member while it is carried on the hollow die 13. As shown in Figure 3, downward movement of the upper member 28 depresses the supporting plate 22 in order that the cylindrical recess 29 may be forced downwardly over the hollow die 13 the desired distance.

Figure 2 best illustrates that an annular ring 34 is sheared or trimmed from the sheet metal member 21 at the first portion of the downward stroke of the upper member. Due to the centering finger engaging with the centering bushing, only a very small clearance between the punch 27 and the die 13 need be provided. This insures a hole of the desired size being formed in the sheet metal member and the exact fitting of the punch and die aid in forming a smooth, clean hole in the metal sheet 21. Formation of the

smooth hole through the sheet metal member means that the ordinary reaming or polishing of the metal outlining the hole before that metal can be drawn, is not required, whereby the drawing operation may be performed in the same downward stroke of the outer member 28 as is the shearing or trimming operation. The apparatus provided by the present invention permits practice of this improved trimming and drawing method whereby the production of integral, drawn out bosses or other protuberances on metallic members is facilitated and the objects of the invention are achieved.

While one embodiment of the invention has been completely illustrated and described herein, it will be understood that various modifications thereof may be made without departing from the scope of the invention as defined in the appended claims.

What is claimed is:

1. Apparatus for forming protuberances in metallic members comprising a base plate, an apertured supporting plate, springs mounting said supporting plate on said base plate, a hollow die carried by said base plate and extending through said apertured supporting plate, a centering bushing slidably received in said hollow die, a spring supporting said centering bushing on said base plate, an upper member having a recess therein adapted to be moved down around said hollow die, a punch carried by said upper member to engage with said hollow die and shear off any material thereon, and a centering finger carried by and extending downwardly from said punch to engage with said centering bushing and center said punch relative to said hollow die prior to engagement thereof.

2. Apparatus for forming protuberances on metallic members comprising a base plate, an apertured supporting plate carried on said base plate, a hollow die carried by said base plate and extending through said apertured supporting plate, a centering bushing slidably received in said hollow die, an upper member, a punch carried by said upper member to engage with said hollow die and shear off any material thereon, said upper member having a recess formed therein around said punch to form a chamber adapted to receive said die therein, said die being adapted to force any material thereon against the portion of said upper member defining said recess and draw out such material to form a protuberance thereon, and a centering finger carried by and extending downwardly from said punch to engage with said centering bushing and center said punch relative to said hollow die prior to engagement thereof.

ARCHIBALD M. BROWN.
